United States Patent

Des. 237,445
Patented Nov. 4, 1975

237,445

CRUET

Peter L. Schweizer, Liberty Center, Ohio, assignor to
Owens-Illinois, Inc.

Filed Apr. 5, 1974, Ser. No. 458,132

Term of patent 14 years

Int. Cl. D7—01

U.S. Cl. D7—59

FIG. 1

FIG. 2

FIG. 3

FIG. 4

FIG. 1 is a front elevational view of a cruet showing my new design;

FIG. 2 is a top plan view thereof;

FIG. 3 is a side elevational view thereof; and

FIG. 4 is a sectional view taken on line 4—4 of FIG. 3.

The back is the same in appearance as the front which is shown in FIG. 1, and the side opposite that seen in FIG. 3 is the same in appearance as the side shown in FIG. 3.

I claim:

The ornamental design for a cruet, substantially as shown and described.
